H. A. SCHMIDT,
STYLOGRAPHIC INK PENCIL,
FILED APR. 6, 1920.

Inventor
HENRY A. SCHMIDT
By his Attorney
Joseph F. O'Brien

UNITED STATES PATENT OFFICE.

HENRY A. SCHMIDT, OF COLLEGE POINT, NEW YORK.

STYLOGRAPHIC INK PENCIL.

Application filed April 6, 1920. Serial No. 371,718.

To all whom it may concern:

Be it known that I, HENRY A. SCHMIDT, a citizen of the United States, and a resident of College Point, in the county of Queens and State of New York, have invented certain new and useful Improvements in Stylographic Ink Pencils, of which the following is a specification.

This invention relates to improvements in 10 stylographic ink pencil.

One of the objects of this invention is to produce in a stylographic ink pencil a firm and immovable writing point in which the stylus will be maintained during the operation 15 of writing in properly adjusted stationary relationship to a tubular point and the ink duct or channel will in the act of writing at all times permit the issuance therethrough of an even supply of writing fluid while at 20 the same time my invention enables the ready manual movement or reciprocation of the stylus outwardly from its writing position for the purpose of breaking any seal in the ink duct caused by capillary attraction 25 or the cleaning away from such duct of any obstruction caused by the thickening of the ink or the deposit of sediment which would render the ink pencil inoperative, and to this end my invention comprises a body having 30 an ink reservoir and a tubular point through which ink is discharged; an air tube or passage extending from an air chamber at the upper part of the body downwardly to the point section thereof; a stylus or needle 35 preferably extending through said tube and mounted to move in said point and to have an inward limit of movement so fixed as to cause the outer end of the stylus to bear immovably and jointly with the tubular point 40 against the paper and coat therewith while writing but to be movable outwardly beyond its writing position preferably by means of a manually-actuated plunger located at the opposite end of the body, which plunger also 45 preferably is provided with a piston reciprocable in an air chamber which upon actuation forces air through an axial air tube and assists in freeing the ink duct or passage and maintaining a flow therethrough.

50 Another object of my invention is to provide in an ink pencil of the character described means for breaking the vacuum which might otherwise be formed above the

ink in the ink chamber within the body or barrel when the pencil is used in writing. 55 For this purpose I provide in such an ink pencil having a main air tube as above described, an auxiliary air passage extending from the lower end of said main passage upwardly to and communicating with the upper end of the ink chamber or reservoir whereby air will be admitted into said upper part of the ink chamber or reservoir above the ink to break said vacuum. 60

With these and other objects in view, the 65 invention comprises the combination of members and arrangement of parts so combined as to co-act and cooperate with each other in the performance of the functions and the accomplishment of the results here- 70 in contemplated, and comprises in one of its adaptations the species or preferred form illustrated in the accompanying drawings, in which—

Fig. 1 is a vertical central section through 75 a pencil embodying my invention with the cap in place and the parts in normal writing position;

Fig. 2 is a similar section showing the plunger partly depressed and the stylus ex- 80 tending below and outside the point;

Fig. 3 is a section on the line 3—3 of Fig. 1; and

Fig. 4 is a section on the line 4—4 of Fig. 1. 85

Referring now to these drawings which illustrate a preferred embodiment of my invention, 1 indicates an ordinary cylindrical body or barrel of hard rubber or similar material, provided at its lower end with a tapering point section 2 of similar material which, as shown, has a metallic tubular point 3 suitably mounted therein, which point 3 has a suitable duct or passage 3^a through which ink is adapted to be fed or supplied in 95 writing. As illustrated, a stylus 4 extends through the said tubular writing point and upwardly through a main air channel or passage 5 located axially in an air tube 6 suitably positioned within the barrel 1 so 100 as to provide concentric therewith an ink reservoir 7 within said barrel 1. As shown, the air tube is connected to and extends through a partition 8 at the upper end of the barrel between the ink reservoir 7 and an air chamber 9 so as to permit said main air 105

channel 5 in the tube 6 to communicate with the air chamber 9 which is provided with an opening or port 10 to the atmosphere. The stylus 4 after passing through the tubular point 3 and through said axial air channel 5 and through the air chamber 9, is connected at its upper end to a plunger 11 movable by a spring 14 and having an actuating portion 13 projecting above a plug 12. The plunger 11 is, as shown, provided with a piston 15 moving in the air chamber 9 so that manual operation of the plunger 11 will force air from the air chamber 9 through the air duct 5 to the point section of the ink reservoir, and a spring 14 is disposed in the air chamber between the partition 8 and said piston so as normally when writing to retain the piston 15 against this plug 12 and the stylus 4 in fixed or immovable relation to the tubular point 3, said stylus being so arranged that the outer end thereof will, when the piston is in the position just described at its inward limit of movement, bear jointly with said tubular point 3 on the paper in writing. A downward movement of said piston will compress said spring and cause an outward movement of the stylus 4; but will enable the reciprocation of the stylus 4 through the passage 3^a in the point 3 to break any capillary seal and clean away any obstruction in said point, thus procuring an initial supply and flowing of ink through the same. This movement of the piston 15 and stylus 4 is preferably effected by manual manipulation or pressure upon the end 13 of the plunger 11.

I also preferably provide in the air tube 6 an auxiliary air passage 16 extending from the lower portion of the air tube 6 upwardly and parallel to the main air channel 5 and having an air port 16^a communicating with the upper end of the ink chamber so that any vacuum which may be formed when the pencil is brought into vertical position for writing will be broken by the equalization of pressure behind the ink in said ink chamber 7. A cap 17 is provided with a cushion 18 of cork or other suitable material and the tubular point is preferably forced into said cushion when the cap is placed on the same and the pen is preferably carried in a position with the point extending downwardly.

Having described my invention, I claim:—

1. A stylographic ink pencil comprising a body having an ink reservoir and a tubular writing point, an air chamber above said ink reservoir, an air tube having an air passage extending from said air chamber downwardly through the ink reservoir to a place adjacent to the writing point; a stylus mounted in said tubular point and extending upwardly through said air passage and into said air chamber; a plunger connected to said stylus and movable in said air chamber, a suitable stop in said air chamber for said plunger; means for automatically forcing said stylus against said stop to move the same into writing position and a finger portion on said plunger to permit manual movement of the stylus outwardly beyond its writing position.

2. A stylographic ink pencil comprising a body having an ink reservoir and a tubular writing point, an air chamber above said ink reservoir, an air tube having a passage 75 extending from said air chamber downwardly through the ink reservoir to a place adjacent to the writing point and a piston movable in said air chamber.

3. A stylographic ink pencil comprising a body having an ink reservoir and a tubular writing point, an air chamber above said ink reservoir, an air tube having a passage extending from said air chamber downwardly through the ink reservoir to a place adjacent 85 to the writing point, and also having another passage extending from its lower end upwardly to and communicating with the upper end of the ink reservoir.

4. A stylographic ink pencil comprising a body having an ink reservoir and a tubular writing point, an air chamber above said ink reservoir, an air tube having an air passage extending from said air chamber downwardly through the ink reservoir to a place 95 adjacent to the writing point, and also having another passage extending from its lower end upwardly to and communicating with the upper end of the ink reservoir and a piston movable in said air chamber.

5. A stylographic ink pencil comprising a body having an ink reservoir and a tubular writing point, an air chamber above said ink reservoir, an air tube having an air passage located axially of said body and extending 105 from said air chamber downwardly to the ink reservoir to a place adjacent to the writing point, a stylus mounted in said tubular point and extending upwardly through said axial air passage and into said air chamber, 110 a piston movable in said air chamber and connected to said stylus, a plunger connected to said piston and extending through the opposite end of the pencil body and means for automatically forcing the plunger and 115 stylus against the upper end of said air chamber.

6. A stylographic ink pencil comprising a body having an ink reservoir and a tubular writing point, an air chamber above said 120 ink reservoir, an air tube having an air passage located axially of said body and extending from said air chamber downwardly to the ink reservoir to a place adjacent to the writing point, and also having another passage 125 extending from its lower end upwardly to and communicating with the upper end of the ink reservoir, a stylus mounted in said tubular point and extending upwardly through said axial air passage and into said 130

air chamber, a piston movable in said air chamber and connected to said stylus, a plunger connected to said piston and extending through the opposite end of the pen-
cil body and means for automatically forc-
ing the plunger and stylus against the upper
end of said air chamber.

In witness whereof, I have signed my name to the foregoing specification in the presence of two subscribing witnesses.

HENRY A. SCHMIDT.
